CLASSIFIER

Hazlitt Alva Cuppy, San Francisco, Calif.

Application September 8, 1931, Serial No. 561,718

10 Claims. (Cl. 209—144)

The present invention relates to improvements in classifiers and has particular reference to a classifier adapted to be used for classifying sugar, cocoa, and the like, where it is desired to reduce 5 the material to extremely fine particles.

The principal object of the invention is to provide a classifier of the character described in which there are no moving parts and in which the classifying is carried out in several stages by 10 directing a material laden fluid through the device, which is constructed to successively remove the material from the fluid.

Another object of the invention is to provide a device of the character described in which the 15 classifying operation is carried on in a continuous procession, the same fluid being used over and over again whereby the fluid is always kept at the proper temperature for the best results and moisture conditions.

20 A further object of the invention is to combine three different units into one system, the first unit serving to classify the material so as to separate the lighter particles from the heavier ones and to return the heavier ones to a mill for further crushing or grinding, while the second unit 25 is designed to separate further material from the fluid carrying the same, and the third unit collects the remaining material and returns the fluid to the first unit and the mill, means being provided for allowing an excess of fluid to dissipate 30 into the atmosphere.

It is further proposed in the present invention to provide improvements in the details of construction and particularly in the classifying 35 means as such.

The preferred form of my invention is illustrated in the accompanying drawing in which

Figure 1 shows partly in elevation and partly in vertical section the complete system containing 40 a separator and a dust collector and an air filter;

Figure 2 a detail view in vertical section of a discharge means for the material laden fluid;

Figure 3 a horizontal section taken along line 3—3 of Figure 2;

45 Figure 4 a horizontal section taken along line 4—4 of Figure 1; and

Figure 5 a vertical section taken along line 5—5 of Figure 4.

While I have shown only the preferred form of 50 my invention it should be understood that various changes or modifications can be made within the scope of the claims hereto attached, without departing from the spirit of the invention.

In its preferred form my invention comprises 55 a separator 1, a dust collector 2 and an air filter

3. The separator 1 consists of a cylindrical container 2' having a funnel 3' at the bottom and a frusto-conical top 4. A conduit 5 extends centrally into the container from the bottom and is connected to a mill (not shown) from which a material laden fluid is conducted into the conduit under pressure. The conduit terminates substantially at the top of the funnel 3' and is provided at its upper end with a plurality of lateral apertures 6 through which the fluid can be discharged, a plurality of blades 7 giving to the fluid a whirling motion. The conduit 5 is covered by a head 8 presenting a conical face upwardly and also having a cone 9 projecting into the conduit for diverting the material laden fluid into the 15 apertures 6.

Surrounding the upper end of the conduit 5 I provide a funnel 10 against the wall of which the material and the fluid are discharged in whirling movement. The funnel 10 terminates at its bottom in an outwardly flaring flange 11 which forms an annular passage with a second flange 12 spaced therefrom for an air-blast entering through the pipe 13, the two flanges 11 and 12 being suitably connected by walls 13' and 14 to provide a complete enclosure for the compressed air.

It will be noted that the construction so far described causes the material laden fluid to be discharged in a whirling movement into the funnel 10, while at the same time an air-blast rises 30 between the flanges 11 and 12 and passes through the whirling material for carrying the lighter particles upward, while the heavier particles are allowed to gravitate downward into the funnel 3' and the discharge conduits 15, which return the 35 heavier particles to the mill by means not shown in the drawing.

Surmounting the conduit 5 there is a second conduit 16 terminating at its upper end in a funnel 17 provided with a cylindrical flange 18. The top of the cylindrical flange 18 is substantially on a level with the top of the cylinder 1 and is dimensioned to leave a passage between the same through which the air-blast carrying the lighter particles of the material is conducted. When 45 leaving this passage the air-blast strikes the conical wall of the top and is diverted toward the funnel 17 by means of a frusto-conical flange 19 and here a second classification takes place, the heavier particles gravitating toward the bottom 50 of the funnel 17, while the fluid carrying the lighter particles passes into the conduit 20, the mouth-piece 21 of which extends centrally into the upper portion of the funnel 17. The heavier particles separated during the second classification 55

pass through the conduit 16 and are deflected by the cone 8 to mix with the whirling material in the funnel 10 where they are again subjected to classification, either following the upward stream 5 through the cylinder 2 or dropping downward through the conduits 15. When the particles passing downward through the conduit 16 strike the cone 8 they are not only diverted, but also comminuted and particularly lumps that have 10 been formed are broken up.

The mouth-piece 21 of the conduit 20 may be raised and lowered by means of a rod 21 extending through the top of the housing 1 whereby the amount of material to be carried by the fluid 15 through the conduit 20 may be adjusted. As the mouth-piece 21 is lowered it approaches the bottom of the funnel 17 and exerts greater suction on the particles gathered there so that more material and comparatively heavier particles are entrained in the fluid. As the mouth-piece 21 is raised the distance between it and the bottom of the funnel is increased whereby the effect of the suction is lessened and the amount of material entrained is decreased. The conduit 20 connects 20 with the dust collector 2, a fan 22 being preferably interposed to boost the draft. The fluid is discharged into a cylindrical chamber 23 in tangential direction so that again a whirling motion takes place in this chamber. Suspended from 25 the chamber there is a long funnel 24 and the heavier particles of the material entrained in the fluid drop toward the bottom of the funnel and are discharged through an opening 25 to furnish the first product known as fine sugar, if the device is used for classifying sugar. A conduit 26 extends from the top into the chamber 23 to receive the fluid and lighter material carried thereby, a baffle plate or disc 27 being provided in spaced relation to the mouth of the conduit 26 to 30 prevent direct suction on material aggregating in the lower end of the funnel and formation of a vacuum.

The fluid with the lightest particles entrained therein passes through the conduit 26 into the air filter 3 and is first discharged into an annular chamber 28, see Figure 4, enclosed in a housing 29. The chamber 28 is provided with a bottom 30 having a comparatively large central opening 31. Some of the material entrained in the fluid is thrown outward and reaches any one of a plurality of vertical pipes 32 communicating with the chamber through slits 33. The other material gradually works toward the opening 31 in the bottom and is collected by any one of a large number of stockings 34 suspended from the housing 29 and all the material passing through the vertical pipes 32 and the stockings 34 is received in a funnel 35 and discharged through the bottom thereof to form the second or superfine product. A conduit 36 extends centrally into the chamber 28 and is adapted to receive the fluid which is now divested of all material. A second fan 37 is preferably used for increasing the draft and a conduit 38 at the discharge end of the second fan 60 connects with the pipe 13 of the separator so that the same fluid is again passed into circulation and is used continuously. If it should happen through some irregularity in operation that the pressure in the air filter is too high for the fan 37 to take care of the fluid it is dissipated into the atmosphere through the stockings 34. The conduit 36 also connects through the pipe 39, with the mill (not shown) so as to be in circuit with the intake conduit 5.

75 The operation of the device will be readily un-

derstood from the foregoing description. The material laden fluid is forced under pressure through the conduit 5 and discharged into the funnel 10 in a whirling motion. An air-blast emanates from between the flanges 11 and 12, 5 passes through the whirling material and entrains the lighter particles thereof, while the heavier particles drop through the conduits 15 to be returned to the mill. It will be noted that the air-blast has to travel through a considerable distance to the cylinder 2' so that there is ample chance for the heavier particles to separate from the lighter particles. The air-blast carrying the lighter particles is then diverted into funnel 17 10 where a second separation takes place, the heavier particles dropping through the conduit 16 upon the cone 8 and joining the whirling material in the funnel 10 for further classification, while the lighter particles are entrained in the fluid and pass into the dust collector 2. Here a new classification takes place and the heavier particles are 15 discharged through the bottom of the funnel 24 to form the first product, while the lighter particles are carried by the fluid into the air filter. Here all the material is separated from the fluid passing 20 either through the pipes 32 or the stockings 34 to emanate from the funnel 35 as superfine product. The fluid itself is then returned through the conduits 38 and 39 into the pipes 13 and 5 for a 25 renewal of the entire operation.

30

I claim:

1. In a classifier, a frusto-conical wall, means for passing an air blast therethrough from below and means for discharging material to be classified into the airblast from the center of the 35 frusto-conical wall, a cylindrical wall connecting with the upper end of the frusto-conical wall for guiding the blast and a second frusto-conical wall arranged at a distance from the first frusto-conical wall for restricting the air blast passage, a 40 baffle plate surmounting the second frusto-conical wall for diverting the air blast centerwise and an outlet conduit having means for adjusting the position of its mouth relative to the baffle.

2. In a classifier, a separator having means for 45 classifying material carried by an air blast directed therethrough, a dust collector connected to the separator and adapted to further collect material from the air blast, an air filter connected to the dust collector and including a cyclone 50 and stocking suspended therefrom and a conduit connecting the cyclone to the separator for returning part of the air blast to the separator for continuous circulation while other air is dissipated through the stockings.

3. In a classifier of the character described, a vertical pipe having slots at the upper end thereof, vanes projecting angularly from the pipe adjacent the slots for imparting swirling motion to an air blast passing through the pipe and the 60 slots and a closure for the upper end of the pipe, having a cone projecting into the pipe for diverting the air blast into the slots.

4. In a classifier of the character described, a vertical pipe having slots at the upper end thereof, vanes projecting angularly from the pipe adjacent the slots for imparting swirling motion to an air blast passing through the pipe and the slots, a closure for the upper end of the pipe, a frusto-conical wall surrounding the upper end of the pipe and having a flange projecting outwardly from the lower end thereof, a second flange running parallel to the said flange and forming a frusto-conical passage therewith, and 70 75

means for directing an air blast through the said passage toward the upper end of the pipe.

5. In a classifier of the character described, a vertical pipe having slots at the upper end thereof, vanes projecting angularly from the pipe adjacent the slots for imparting swirling motion to an air blast passing through the pipe and the slots, a closure for the upper end of the pipe, a frusto-conical wall surrounding the upper end 10 of the pipe and having a flange projecting outwardly from the lower end thereof, a second flange running parallel to the said flange and forming a frusto-conical passage therewith, and means for directing an air blast through the said 15 passage toward the upper end of the pipe, the two flanges having an annular enclosure connecting the same.

6. In a classifier of the character described, a vertical pipe having discharge slots in the upper end thereof, a closure for the end of the pipe, a frusto-conical wall surrounding the upper end of the pipe and having a flange projecting outwardly from the lower end thereof, a second flange running parallel to the said flange and forming a frusto-conical passage therewith and means for directing an air blast through the said 20 passage toward the upper end of the pipe.

7. In a classifier of the character described, a vertical pipe having discharge slots in the upper end thereof, a closure for the end of the pipe, a frusto-conical wall surrounding the upper end of the pipe and having a flange projecting outwardly from the lower end thereof, a second flange running parallel to the said flange and forming a frusto-conical passage therewith and means for directing an air blast through the said 25 passage toward the upper end of the pipe, the two flanges having an annular enclosure connecting the same.

8. In a classifier of the character described, a vertical conduit, means for passing material therethrough from below, means for discharging the material laterally, means for directing an air blast through the discharged material from 30 below whereby lighter particles are carried up-

ward and heavier particles are allowed to drop and means for again classifying the lighter particles including a second conduit above and aligned with the first conduit for returning the heavier ones thereof to the original place of lateral discharge, with a conical head on the first conduit serving to divert and comminute the material.

9. In a classifier of the character described, a vertical conduit, means for passing an air current and material entrained therein through the conduit from below, means connected with the conduit causing the air current to discharge the material laterally whereby the discharged material is scattered, means for directing an air blast 35 through the discharged material from below whereby lighter particles are carried upward and heavier particles are allowed to drop, an enclosure for the said particles at and above the discharge and means within said enclosure for again 40 classifying the lighter particles, the said means having a second conduit within the enclosure above and aligned with the first conduit and means for returning the heavier ones of the lighter particles through the second conduit to the original 45 place of discharge.

10. In a classifier of the character described, a vertical conduit, means for passing an air current and material entrained therein through the conduit from below, means connected with the 30 conduit causing the air current to discharge the material laterally whereby the discharged material is scattered, means for directing an air blast through the discharged material from below for 35 classifying the same, a relatively long cylinder for guiding the air blast a considerable distance above the conduit discharge, a central funnel for restricting the air blast at the upper end of the cylinder, a central outlet over the funnel and means for 40 diverting the air blast into the latter outlet, the funnel serving to guide part of the material entrained in the air blast back to the discharge area of the first conduit.

HAZLITT ALVA CUPPY.
